GABRIEL BAUM, OF BROOKLYN, NEW YORK.

DISPLAY DOLL AND DRESS OUTFIT.

Application filed August 20, 1921. Serial No. 493,823.

To all whom it may concern:

Be it known that I, GABRIEL BAUM, a citizen of the United States, and a resident of the city of New York, borough of Brooklyn, 5 in the county of Kings and State of New York, have invented a new and improved Display Doll and Dress Outfit, of which the following is a description.

My invention relates to a display outfit 10 and especially is intended for the display of a child's dress. It is well recognized that the mere appearance of a dress on a counter or in a box does not enable one to determine the effect of the dress when worn, and it is 15 the general object of my invention to display the dress in folded form in small compass and at the same time to display the appearance of the dress when worn, whereby an intended purchaser may readily judge as 20 to the desirability not only of the dress itself as to material, design, and style, but may instantly glimpse the appearance and effect of the dress when worn, and this, without disturbing or wrinkling the folded dress, 25 the outfit thus preventing repeated handling and wrinkling of the dress.

The stated object is attained by providing an outfit in which a miniature dressed figure is held in the container in juxtaposition to 30 the folded dress, and the doll's dress corresponding in every respect with the child's dress, the one serving to satisfy the enquirer as to the general appearance of the dress in full size and to simultaneously enable the 35 enquirer to determine the appearance of the same dress, as worn.

Reference is to be had to the accompanying drawings forming a part of this specification, it being understood that the drawings are merely illustrative of one embodiment 40 of the invention.

Figure 1 is a perspective view of a display doll and dress outfit constituting an actual embodiment of my invention;

45 Figure 2 is a perspective view of the child wearing the dress of the outfit and carrying the dressed doll of the outfit.

In carrying out my invention in accordance with the illustrated example a box 10 50 is provided having tie strings 11, 12 for holding in fixed position a child's dress 13 and a dressed doll 14, whereby the dress will be held in folded position to display the nature and quality of the material as well as the 55 pattern of the fabric and the style and ornamentation of the dress.

The dress 13^a of the doll 14 constitutes an exact or substantial representation in miniature of the actual dress 13 being made of the identical material, the design thereof, and 60 in the same style, and preferably with the same ornamental elements. If desired, the doll's dress may be left without certain ornamental elements, such, for example, as embroidery elements, thereby leaving it for the 65 child to produce the same embroidery elements on the doll's dress as appears on the child's dress. The actual dress and the miniature representation thereof are here shown with bloomers 15, 15^a, respectively, 70 and with ornamental elements 16, 16^a, respectively. The element 13^b represents the child's neck ribbon suspended from a collar 13^d and 13^e represents the corresponding ribbon on the collar 13^c of the doll. Since the 75 mere appearance of the unworn dress does not enable one to judge the effect of the dress when worn, intending purchasers require usually that the dress be placed against the child and otherwise handled in ordinary 80 practice. With my improved display outfit no disturbance of the actual dress is necessary because all the information needed can be ascertained, the intended purchaser being enabled to take in at one glance both the actual 85 dress and the exact miniature representation thereof, showing the effect when worn. Thus, the actual dress is at all times maintained in its most attractive appearance with 90 obvious advantages to the merchant.

In addition to the stated advantages and merits of the display outfit the important result is obtained that people are enabled to cultivate good taste with respect to the garb of a child and the related garb of a doll carried by the child.

I would state in conclusion that while the illustrated example constitutes a practical embodiment of my invention, I do not limit myself strictly to the exact details herein 100 illustrated, since manifestly the same can be considerably varied without departure from the spirit of the invention as defined in the appended claims.

Having thus described my invention, I 105 claim:

1. As a new article of manufacture, a display doll and dress outfit consisting of a vendable unit comprising a container, a child's made dress held therein, and a dressed doll 110 held in said container in juxtaposition of the child's dress, the doll's dress being in minia-

ture, an exact representation of the child's dress as to material, design, and cut, to display the set and appearance of the said child's dress when worn and without disturbance thereof in the container.

2. As a new article of manufacture, a display doll and dress outfit consisting of a vendable unit comprising a container, a folded child's dress therein, and a dressed

doll in said container, the doll's dress being 10 in miniature a representation of the child's dress as to material, design, and cut to display the set and appearance of said child's dress when worn and without disturbance thereof from its folded condition in the container.

GABRIEL BAUM.
